UNITED STATES PATENT OFFICE.

WILLIAM R. BARSTOW, OF OAKLAND, CALIFORNIA.

PUNCTURE-REPAIRER.

1,048,385.

Specification of Letters Patent. Patented Dec. 24, 1912.

Application filed September 13, 1911. Serial No. 649,025.

To all whom it may concern:

Be it known that I, WILLIAM R. BARSTOW, a citizen of the United States, residing at Oakland, in the county of Alameda and State of California, have invented new and useful Improvements in Puncture-Repairers, of which the following is a specification.

This invention relates to repair devices and more particularly to that type which are adapted to repair punctures and small blow-outs in the inner tubes of pneumatic tires.

A further object of the invention is to provide a simple, cheaply constructed device of this character which may be readily applied to the tube to close the puncture opening therein and which, in its application, will not bruise or in any way affect the remainder of the tube.

Further objects of the invention will appear as the following specific description is read in connection with the accompanying drawing, which forms a part of this application, and in which:

Figure 1 is an elevation of the device applied to a tire. Fig. 2 is a sectional view through the device and tire. Fig. 3 is a perspective view of the inner member. Fig. 4 is a similar view of the outer member. Fig. 5 is a perspective view of the clamping member.

Referring more particularly to the drawing, 1 represents an ordinary inner tube of a pneumatic tire and 2 generally indicates the puncture closing device. This puncture closing device comprises a substantially saucer-like disk 3 having a standard 4 projecting from its center concave portion, which standard is exteriorly threaded and preferably hollow, as shown, to reduce the weight of the article. A similar saucer-like disk 5, having a central aperture 6 therein to receive the standard, is provided and a clamping member consisting of a substantially flat disk having an internally threaded collar or nipple 8 projecting therefrom is also provided to clamp the members 3 and 5 together. Both of the members are provided with annular ribs 9 which are pressed up from their bodies, so as to produce in the member 5 a channel 10 which is adapted to be entered by the rib on the member 3 or, more correctly speaking, so that the rib on the member 3 will press a portion of the tube between the disks up into the channel 10. The said saucer-like disks 3 and 5 are provided on their opposing faces

with a layer of canvas 10', thereby preventing the rubber from chafing.

The outer edges of the disk 7 are thinned out so as to lie flat against the outer disk 5, 60 as shown at 11, and suitable holes 12 are formed in the disk to receive a spanner wrench or similar tool by which the clamping member may be threaded upon the standard 4.

In practice, the puncture is first located and an opening made in the tire at the puncture point which will be of sufficient size, after stretching the tube, to permit the passage of the lower disk 3. This opening 70 may be formed by a pair of pliers having semi-circular cutting blades thereon and the tire folded along the puncture line so that, when the jaws are brought together, a semi-circular cut is made which, when the tire 75 is open, will form a circular opening. A string is tied around the standard and the disk 3 inserted through the opening formed, and the standard pulled out of the opening, still holding on to the string while the 80 second disk 5 is placed down over the standard. The string is then removed and the clamping member 7 screwed down upon the standard, so that the outer edge of the nipple 85 abuts the disk 5 and the outer edge of the disk 7 rests upon the concave convex portion of said disk. The clamping member is then tightened up by a spanner or other suitable implement.

It will be noticed that by the use of the 90 outer disk 5 the clamping member will not wear the tire in being screwed home and that by the use of a disk of this character having the nipple 8 the tire is positively gripped around the standard and resiliently clamped 95 between the outer and inner disks adjacent the edge of the same. These devices may be made of any suitable material and of any size or of many sizes, so as to be adaptable for punctures or small blow-outs and may be 100 constructed to operate upon the outer casing or the inner tube with equally advantageous results.

Having thus described the invention, what I claim as new is:

A puncture repair device comprising inner and outer concavo-convex disks, a hollow externally threaded standard projecting upwardly and centrally on the concave portion of the inner disk, the outer disk having an aperture to receive the said standard, said inner and outer disks being

formed with stamped up annular ribs, a flat clamping disk provided with apertures and having an integrally threaded downwardly and centrally disposed nipple there-in for surrounding the said hollow standard, said nipple engaging the outer disk adjacent its aperture for clamping the disks together and said flat disk engaging with the outer disk adjacent the peripheral edge thereof and adapted to press the inner and outer disks together at an independent line between the outer peripheral edges of said disk and the said annular ribs, the face of the flat clamping disk gradually tapering from the threaded nipple to the peripheral

edge thereof, thereby forming its entire outer peripheral edge thin, permitting the underneath peripheral edge of the disk to lie flat against the outer face of said outer disk and preventing the marring of the annular rib carried thereby, the said inner and outer disks having their opposed faces covered with canvas to prevent the chafing of the rubber. 20

In testimony whereof I affix my signature 25
in presence of two witnesses.

WILLIAM R. BARSTOW.
